UNITED STATES PATENT OFFICE.

RODNEY G. RICHARDSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed May 23, 1920, Serial No. 334,353. Renewed July 21, 1926.

My invention relates in general to automatic telephone systems, but more particularly to such systems as comprise main and branch exchanges which are interconnected by trunk lines, the branch exchanges being of the type at present used in large numbers to supply telephone service to manufacturing establishments, department stores, and the like; and the principal object of the invention is to provide a new and improved arrangement whereby main to branch exchange calls may be transferred automatically from one station to another at a branch exchange while the calling main exchange subscriber waits on the line.

A number of systems having the general characteristics described above have been designed before this, and have become more or less widely known in the art under the name of "transfer call" or "passing call" systems. These prior systems, however, have been rather complicated, and on this account have been expensive to install, and are subject to numerous troubles in practice, and have not, therefore, gone into as extended a public use as might otherwise have been the case. In particular, the circuits used heretofore involve such a radical change over the ordinary switch circuits that it is practically impossible to modify an existing private automatic exchange to take care of the transfer call feature without entirely rebuilding the switches which often renders the adoption of such circuits of doubtful expediency.

In my improved system disclosed herein, the incoming connectors, which are the switches in which the main to branch exchange trunks terminate at the latter point, and which have access to the branch exchange lines, may be of any approved or desired type, and require practically no modification or change. Calls are transferred in the first instance through the medium of the local connectors, one of which is taken for use by any called party who desires to transfer a call, and the control of such local connector being exercised through the medium of a special two way repeater associated with the incoming connector in use and connected thereto by a minimum number of conductors. Thereafter the call may be transferred as often as desired, the incoming

connector and the same or any other idle local connector being operated alternately. 55 Entirely new circuit arrangements are required in order to permit the use of the local connectors in transferring calls, including among other things a special arrangement whereby directive impulses may be transmitted back from a local connector by rapidly reversing the direction of current flow in the trunk line; and in view of these facts, while the main object of the invention is, as stated, the production of a new and 60 improved transfer call system, this being the specific embodiment of the invention shown herein, it is conceived that certain features of the invention will be found to be of value 65 for other purposes and in other systems, and these features therefore are not to be restricted to the specific uses hereinafter described.

Referring now to the drawings, comprising Figs. 1 and 2, I have shown therein by 75 means of the usual circuit drawings sufficient of the equipment in a private automatic exchange to illustrate the invention. In Fig. 1 the reference character D indicates an incoming connector which, as 80 stated, may be of any approved or desired type, although it is here shown in simple form in order not to complicate the explanation. This connector is the terminal of the main to branch exchange trunk line comprising conductors 12 and 13 and constitutes the means whereby such trunk line may be connected with any local line in the branch exchange. Associated with the incoming connector D is a group of relays indicated 85 by reference character E. This group of relays is one of the special repeaters previously referred to and is used in transferring calls initially completed by means of the connector with which it is associated. 90 In Fig. 2, which should be placed above Fig. 1 with corresponding lines at the bottom and top in alignment, I have shown one of the local connectors, which is indicated by reference character H. All the local connectors and all the incoming connectors have common access to the local lines, two of which are shown in the drawing. The telephone stations on these lines are indicated by reference characters A' and A''. All the 95 local lines have access to the local connectors 100 105

through the medium of individual rotary line switches two of which, the line switches individual to stations A' and A², are shown and are indicated by reference characters C' and C². The line switch C is a similar line switch which is assigned to the repeater E, and which is provided for the purpose of giving a called subscriber access by way of the said repeater to the local connectors. 5 Any vacant line switch may be used for this purpose, and usually there will be sufficient extra line switches available, although if they are all in use some additional ones will have to be provided. 10 Having described in general terms the scope of the invention and the character of apparatus involved I will now explain more in detail the operation of the circuits, which can best be done by explaining the process 15 of establishing a main to branch exchange connection and the process of transferring and re-transferring such connection to various local stations. It will be assumed that substation A' is the station to which the connection is to be extended in the first instance. The main exchange may be of any modern two wire type and the main to branch exchange trunk lines may be taken off from some second or third selector level, repeaters 20 being used in the trunks as is customary. The calling main exchange subscriber, then, may obtain access through the medium of his individual line switch and two or more selector switches to an idle trunk line extending 25 to the branch exchange. The line switch is of course operated automatically when the receiver is removed while the selector switches are directively controlled by calling the proper digits on the calling device at 30 the calling station. When the trunk to the branch exchange is connected with, the line and release relays in the repeater pull up and the latter relay closes a holding circuit in the usual manner to maintain the main 35 office switches in operated position. At the same time, a bridge is closed across the two conductors of the trunk line on the outgoing side of the repeater. Assuming that the trunk line comprising conductors 12 and 13 40 is the one connected with, the closure of this bridge completes a circuit for the line relay 14 of the incoming connector D, which relay, upon energizing, closes a circuit for the slow acting release relay 15. The latter 45 relay, upon energizing, prepares the connector for operation in its vertical movement. 50 The subscriber in the main exchange may now call the two last digits in the desired number, these last two digits being the digits 55 in the local number of substation A'. When the dial is operated a series of interruptions is produced in the circuit of the line relay of the main exchange repeater, which the 60 said line relay repeats into the circuit of the line relay 14 of the connector D by produc-

ing a like series of interruptions in the bridge across trunk conductors 12 and 13. Line relay 14 is accordingly deenergized a plurality of times and at each deenergization transmits a current impulse to the vertical magnet 21 over the following circuit: ground at G⁴, armature 24 and its resting contact, armature 25 and its working contact, off normal springs 43 and 41, winding of the slow acting series relay 16, and the 70 winding of the vertical magnet 21 to battery. The above is the circuit over which the first impulse is transmitted. At the first upward movement of the shaft the off normal springs are shifted and the circuit is completed over 80 a new path as follows: armature 25 and its working contact, off normal springs 43 and 42, armature 27 and its working contact (relay 16 being now energized), winding of relay 16, and the winding of the vertical mag- 85 net 21 to battery. By the operation of the vertical magnet the wipers 60-62, inclusive, are raised step by step until they stand opposite the level of bank contacts in which are located the contacts associated with the line 90 of substation A'. The slow acting relay 16, which is energized in series with the vertical magnet, maintains its armature attracted during the vertical operation of the switch, and at the end of the vertical movement de- 95 energizes and transfers the operating circuit from the vertical magnet 21 to the rotary magnet 22.

The calling subscriber may now operate his calling device in accordance with the 100 final digit. As before, a series of interruptions is produced at the repeater in the bridge across the trunk conductors 12 and 13, and the line relay 14 is again deenergized a number of times, transmitting im- 105 pulses to the rotary magnet 22 over the following circuit: ground at G⁴, armature 24 and its resting contact, armature 25 and its working contact, off normal springs 43 and 42, armature 27 and its resting contact, rest- 110 ing contact of armature 32 and the said armature, armature 38 and its resting contact, and the winding of the rotary magnet 22 to battery. Responsive to these impulses the rotary magnet is operated to rotate the 115 switch wipers into engagement with the particular set of bank contacts which is associated with the line of substation A', being the bank contacts indicated in the drawing by reference characters 63-65, inclusive. The slow acting relay 19 is energized in parallel 120 with the rotary magnet and remains in operated position during the rotation of the switch. At its armature 34 relay 19 connects the test wiper 61 with the test relay 18, and at its armature 35 relay 19 closes the operating circuit over a path which is independent of the armature 32 controlled by the test relay 18 in order to guard against the possibility of the latter relay being momentarily 125 130

energized while the test wiper 61 is passing over busy test contacts. Assuming first that the line of substation A' is busy when called as above described, when the test wiper 61 comes to rest in engagement with test contact 64, it will find a ground potential thereon and the test relay 18 will be energized. When the slow acting relay 19 deenergizes an instant later, a locking circuit will be established for relay 18 as follows: ground at G², armature 26 and its working contact, conductor 51, armature 134 and its resting contact, conductor 52, armature 31 and its working contact, contact springs controlled by armature 34, and the winding of relay 18 to battery. In energized position the test relay opens the rotary magnet circuit at its armature 32 and at its armature 33 connects a lead from the busy signalling machine Q to the lower talking conductor. By this latter operation the calling subscriber is given an audible busy signal, and being advised thereby that the desired branch exchange line is for the time being inaccessible, he will replace his receiver.

Having described the operations which take place when the called line is busy, it will now be assumed that the called line is idle. Under these circumstances, when the test wiper 61 comes to rest in engagement with test contact 64, it will find no ground potential and the test relay 18 will not be energized. Then when the slow acting relay 19 deenergizes the following circuit will be completed: ground at G², armature 26 and its right working contact, armature 66 and its resting contact, upper winding of the switching relay 20, resting contact of armature 34 and the said armature, test wiper 61, test contact 64, winding of the switching relay 73 of line switch C', and the winding of the stepping magnet 74 to battery. Upon the closure of the above circuit relays 20 and 73 are energized in series and the latter relay operates to disconnect the line of substation A' from its normal battery and ground connections in the line switch C'. It is noted that the relay 73 is operated only about half way, due to the fact that the line relay of the line switch has not been energized, and the line conductors are not connected through to the line switch wipers. At the connector D when the switching relay 20 is energized it establishes a locking circuit for itself at its armature 39, opens the rotary magnet circuit at its armature 38, connects ground G² to the test wiper 61 at its armature 37, and at its armatures 36 and 40 closes the talking conductors through to the line wipers of the connector.

The connection having been finally completed, ringing current from the generator Gen is projected intermittently out over the line of substation A' in the usual manner to operate the bridged ringer at the substa-

tion. It will be noticed that the return path for the ringing current includes the upper winding of the ring cut-off relay 17. When the called subscriber responds by removing his receiver the ring cut-off relay is energized and establishes a locking circuit for itself at its armature 29. The ring cut-off relay also opens the ringing circuit at its armatures 28 and 30, and at the working contacts of these same armatures finally completes the talking circuit. The calling subscriber is supplied with talking battery from the line relay in the repeater at the main exchange in the well known manner, while the called subscriber is supplied with talking battery through the windings of the double wound back bridge relay 101. The latter relay is part of the repeater E, the usual back bridge relay in the connector being omitted. Relay 101 is connected across the heavy talking conductors of the connector by means of conductors 47 and 48, and upon energizing closes a circuit for the slow acting relay 102. Relays 101 and 102 remain energized throughout the conversation, but without effect unless the call is to be transferred.

The complete talking connection between the calling substation in the main exchange and the substation A' in the branch exchange has now been established and the calling and called subscribers can converse as desired. We will now assume that for some reason or other it becomes desirable to transfer the call to another local substation in the branch exchange, for example, substation A², Fig. 2. The transfer is accomplished by the called subscriber at substation A' who tells the calling main exchange subscriber to wait a moment and then operates his calling device in accordance with the digits in the telephone number of substation A², the digit 1 being prefixed to the number. The operations which take place in transferring the call will now be explained. When the calling device at substation A' is operated for the digit 1, the back bridge relay 101 in the repeater E is deenergized momentarily and at its armature 114 closes a circuit for relay 103. Upon energizing, relay 103 closes a locking circuit for itself at its armature 120; prepares a circuit for relay 100 at its armature 137, and at its armature 119 prepares a bridge across the heavy outgoing talking conductors 141 and 142 of the repeater which is closed by the back bridge relay 101 when it pulls up after the momentary deenergization. This bridge may be traced as follows: conductor 141, armature 112 and its working contact, armature 119 and its working contact, winding of polarized relay 106, and winding of impedance coil 140 to conductor 142.

The conductors 141 and 142 extend to and terminate in the rotary line switch C and it

- will be obvious that the closure of the bridge across these conductors will complete a circuit for the line relay 151 of the line switch. Upon energizing, the line relay completes a circuit extending through the switching relay 150 and the stepping magnet 152 in series at its armature 157, and at its armature 156 connects the test wiper 161 to the above circuit at a point midway between the switching relay and the said stepping magnet. The operation now depends upon whether the test contact with which the test wiper 161 is in engagement is busy or is not busy. If this test contact is busy it will have a ground potential upon it, the switching relay 150 will be short circuited, and the stepping magnet 152, which interrupts its own circuit, will operate as a buzzer to advance the switch wipers 160-162, inclusive, step by step in search of a trunk line extending to an idle local connector. This operation will continue as long as the test wiper 161 engages grounded or busy test contacts. However, we may assume that in the present case the connector H is idle when the operation of the line switch is initiated and the test contact 164 therefore is not grounded. Under these circumstances, when the line relay 151 is energized, the switching relay 150 is energized immediately afterwards, with the result that the trunk conductors 141 and 142 are disconnected from the winding of the line relay 151 and from the winding of the impedance coil 159, and are extended by means of armatures 153 and 155, wipers 160 and 162, bank contacts 163 and 165, and conductors 166 and 168 to the upper and lower windings of the line relay 214 of the local connector H, Fig. 2.
- Immediately upon the extension of the closed trunk circuit as above described the line relay 214 will be energized and will close the circuit of the slow acting release relay 215. Upon energizing, relay 215 prepares the circuit of the connector for the vertical operation in the usual manner, and at armature 226 completes a holding circuit extending back to the line switch C over the following path: ground at G⁵, working contact of armature 226 and the said armature, conductor 167, test contact 164, test wiper 161, armature 154 and its working contact, winding of the switching relay 150 and the winding of the stepping magnet 152 to battery.
- It is understood that the above holding circuit is established before the slow acting line relay 151 has had time to deenergize. The holding circuit also serves to maintain a ground potential on test contact 164 and its multiples in order to make the connector H busy.
- Having called the digit 1 with the result that the outgoing trunk from the repeater E has been extended by means of line switch C to the local connector H, the subscriber at
- substation A' may now finish the operation by calling the two digits which compose the local number of substation A². At each operation of the calling device the back bridge relay 101 is deenergized a plurality of times in accordance with the digit called, and at its armature 112 produces a series of interruptions in the bridge across conductors 141 and 142, thereby causing a like series of deenergizations of the line relay 214 of the local connector H. At the same time relay 101 sends a series of impulses through the winding of the slow acting relay 100, which relay is energized at the first impulse and remains in operated position during the series of impulses. At its armature 111 relay 100 opens the lower heavy talking conductor at the repeater and closes the bridge across conductors 141 and 142 over a direct path which extends from conductor 141 by way of armature 112 and its working contact, working contact of armature 116 and the said armature, and the working contact of armature 111 and the said armature to conductor 142. These circuit changes produced by relay 100 are the usual provisions adopted to obtain a more efficient control circuit for the local connector. Relay 100 also connects resistance 144 across the conductors 12 and 13 of the incoming trunk line from the main exchange. This is done in order to prevent any disagreeable sound in the receiver at the calling main exchange telephone while the called party at the branch exchange is operating his dial. The shunting effect of the resistance effectually prevents this, and at the same time permits the main exchange subscriber to hear what is taking place.
- To proceed with the explanation, the interruptions in the bridge across conductors 141 and 142 produced by the back bridge relay 101 cause deenergizations of the line relay 214 of the local connector H, as stated, and the local connector is operated responsive to the calling of the two digits in the local number of substation A² to establish connection with the line extending to such substation. In view of the fact that the local connector is substantially like the incoming connector D, whose operation has already been described, it will be unnecessary to repeat the explanation in detail; but it will suffice to say that the line relay 214 responds to the calling of the first digit to transmit a series of impulses through the slow acting relay 216 and the vertical magnet 221 in series, the vertical magnet being operated to raise the switch shaft step by step until the wipers 260-262, inclusive, stand opposite the desired level of bank contacts. The slow acting relay 216 then deenergizes and transfers the operating circuit to the rotary magnet 222; and when the next and final digit is called the rotary magnet is operated to

rotate the wipers into engagement with the particular set of bank contacts in which the line of substation A² terminates, these bank contacts being indicated in the drawing by reference characters 263, 264, and 265. The slow acting relay 219 is energized in parallel with the rotary magnet and maintains its armature attracted during the rotary movement. When the test wiper 261 comes to rest in engagement with the test contact 264 if the called line is busy the test wiper will find a ground potential on said test contact and the test relay 218 will be energized, establishing a locking circuit for itself when the slow acting relay 219 falls back. The test relay 218 connects a lead from the busy signalling machine Q' to the lower heavy talking conductor and thereby transmits the usual audible signal to both subscribers to advise them that the line of substation A² is busy.

While the busy signal can be heard by both parties it does not prevent them from talking together and we will assume now that the subscriber at substation A' will ask the main exchange subscriber to wait a little longer while he tries the number again. The connector H is released from the busy line by hanging up the receiver at substation A'. This operation causes the back bridge relay 101 to deenergize and open the bridge across conductors 141 and 142, thereby permitting the line relay 214 and the slow acting release relay 215 at the connector H to deenergize. The deenergization of these two relays closes the circuit of release magnet 223 and the connector H is restored in the usual manner. Line switch C is also restored by the breaking of its holding circuit at armature 226 of relay 215. At the repeater E the deenergization of relay 101 is followed by the deenergization of slow acting relay 102, and the latter relay breaks the locking circuit of relay 103 at armature 115.

The receiver is hung up only for an instant and when removed relays 101 and 102 are again energized. Since relay 103 has deenergized, however, nothing further happens until the subscriber at substation A' begins to call again. The same number or any other number may of course be called now, but for convenience it will be assumed that the number of substation A² is tried over again. When the calling device is operated in accordance with the digit 1 the relay 103 is locked up, the bridge is closed across trunk conductors 141 and 142, and the line switch C is again operated. Assuming that the connector H is selected as before, this connector may now be reoperated to again establish connection with the line of substation A². This time, if we assume that the line is idle, when the test wiper 261 comes to rest in engagement with test contact 264 it

will find no ground potential and the test relay 218 will not be energized. The slow acting relay 219 now deenergizes and closes a circuit for the switching relay 220 in series with the switching or cut-off relay 273 of 70 the line switch C². The latter relay is operated part way to disconnect the line of substation A² from its normal battery and ground connections in the line switch. Relay 220 is energized also and closes a locking circuit for itself, opens the rotary magnet circuit, grounds the test wiper, and closes the talking conductors through to the line wipers. The usual signalling circuit is now established and the bell at substation A² 80 is rung automatically to notify the subscriber that he is being called.

In case no response is secured the subscriber at substation A' may of course hang up and release the connection in order to try some other number, the release being accomplished the same as in the previous case where the called line was busy. In view of this fact, no further explanation need be made as to this feature, and it will be assumed that the subscriber at substation A² answers when his bell is rung. When the receiver is removed the ring cut-off relay 217 is energized and locked up, the ringing circuit is broken, and the talking circuit through the connector H is finally completed. The transmitter at substation A² is now supplied with talking battery through the windings of the back bridge relay 200 of connector H, and this relay, upon energizing, reverses the direction of current flow in the trunk coming from the repeater E. As a result, the polarized relay 106, which is included in the bridge at the repeater and which heretofore has remained inoperative, 105 now operates its armature to close the circuit of the line relay 107. The latter relay, upon energizing, closes the circuit of slow acting relay 108 which upon energizing in turn prepares various circuits which will be 110 discussed later.

The calling main exchange subscriber, the branch subscriber at substation A', and the branch subscriber at substation A² are now all connected together in a three cornered talking circuit. They may converse together if desired, or the subscriber at substation A² can hang up his receiver to permit the subscriber at substation A' to release the connection and call another number. However, in order to proceed with the explanation, it will be assumed that the subscriber at substation A' hangs up now, leaving the main exchange subscriber and the branch subscriber at substation A² to converse between themselves. When the receiver is replaced at substation A' relays 101, 102, and 103 are deenergized as before described, but the connection to substation A² is not released because the bridge across conductors 141 and 125

142 is not broken, this bridge having been completed over a new path by means of armature 130 of relay 108. Relay 102 having deenergized, a circuit is completed for relay 109 as follows: ground at G^2 , armature 26 and its working contact, conductor 51, armature 115 and its resting contact, working contact of armature 129 and the said armature, and the winding of relay 109 to battery. Upon energizing, relay 109 locks itself at armature 133, closes the bridge across the trunk at a new point at armature 135, removes ground G^2 from conductor 52 by means of armature 134 (this unlocks the switching relay 20 and the ring cut off relay 17 of the incoming connector D), and at armature 136 closes a circuit for the release magnet 23 of connector D as follows: ground at G^6 , armature 118 and its resting contact, working contact of armature 136 and the said armatures, armature 125 and its resting contact, conductor 49, off normal springs 44, and the winding of the release magnet 23 to battery. By the operation of the release magnet 23 the connector D is restored in the usual manner.

It will be assumed now that for some reason of other it becomes necessary to transfer the call to the third substation in the branch exchange. This may of course be any other substation but for convenience it will be assumed that the call is to be transferred back to substation A'. The retransfer is accomplished by the subscriber at substation A² who operates his calling device in accordance with the digits in the local number of substation A', the digit 1 being prefixed to the number as in the previous case. When the digit 1 is called the back bridge relay 200 is deenergized momentarily and momentarily reverses the direction of current flow in the trunk and in the winding of polar relay 106 in bridge thereof. The polar relay responds by momentarily interrupting the circuit of the line relay 107 which, upon deenergizing, closes a circuit for the slow acting relay 105 at its armature 128. Relay 105 is accordingly energized and prepares a circuit at its armature 126 for the slow acting relay 104 which is closed by the line relay 107 at armature 127 when it pulls up an instant later. Relay 104, upon energizing, breaks the original energizing circuit of relay 105 at the resting contact of armature 123 but immediately closes an alternative circuit for said relay at the working contact of the same armature, and we now have all three slow acting relays, relays 104, 105, and 108, energized in parallel from the grounded armature 127 of the line relay 107. Other circuit changes produced by relay 104 are the following: The conductors 51 and 52 are again connected at armature 121, the release circuit is opened at armature 125, an operat-

ing circuit for connector D is prepared at armature 122, and a circuit for the slow acting relay 100 is prepared by means of armature 124.

The apparatus is now ready for the transmission of operating impulses to the connector D. When the calling device at substation A² is operated in accordance with the first digit in the local number the back bridge relay 200 is deenergized a plurality of times and produces a series of reversals in the current flow in the trunk. The polar relay 106 is thereby caused to vibrate its armature and brings about a series of deenergizations of the line relay 107 which at each deenergization sends an impulse to the vertical magnet 21 of the connector D over the following path: ground at G^6 , armature 118 and its resting contact, armature 128 and its resting contact, armature 131 and its working contact, armature 122 and its working contact, and conductor 50 to off normal spring 43, where it joins the previously traced operating circuit and continues through the series relay 16 and the vertical magnet 21 to battery. The vertical magnet is thus operated substantially the same as already described to raise the switch shaft step by step until the wipers stand opposite the proper level of bank contacts. At the same time a series of impulses is transmitted to the slow acting relay 100 by means of armature 127, and this relay accordingly is operated and remains in operated position while impulses are being transmitted over the main operating circuit. Relay 100 performs substantially the same functions in the present case as in the case where the call was being transferred for the first time, except that since relay 102 is deenergized and its armature 116 is in retracted position the polar relay 106 is not cut out of the bridge, but only the impedance coil 140.

The calling device at substation A² is now operated in accordance with the last digit and as before a series of reversals is produced in the current in the trunk line to which reversals the polar relay 106 responds and interrupts the circuit of the line relay 107. The line relay now transmits a series of impulses over the operating circuit including conductor 50 to the rotary magnet 22 and the wipers of the connector D are rotated and finally brought to rest in engagement with the bank contacts associated with the line of substation A'. If the line is found to be busy the test relay 18 will be energized and both subscribers will be given the busy signal. The transferring party, who it will be remembered is the subscriber at substation A², can now release the connection and call the same or any other number over again if he so desires. The release is accomplished by hanging up the receiver in the customary manner, as was done under

similar conditions when the call was being transferred in the other direction. When the receiver is replaced the back bridge relay 200 falls back, the current in the trunk line 5 is reversed back to its normal direction of flow and the polar relay 106 opens the circuit of line relay 107. When the latter relay deenergizes the three slow acting relays 104, 105 and 108 are permitted to fall back also 10 and relay 104 disconnects ground from conductor 52 at its armature 121 and also closes the release circuit at its armature 125. The connector D is thereupon restored to normal 15 position as already described. It is noted that relay 109 remains locked up when the release takes place in order to maintain the bridge across the trunk intact.

The same or any other number may now be called again when the receiver is removed 20 again at substation A², the digit 1 being pre-fixed as before. Assuming that substation A' is called again and that the line is found to be idle, the connection will be completed and the bell will be rung in the manner already described. When the subscriber answers the ring cut-off relay 17 will energize 25 to cut off the ringing generator and close the talking circuit. The back bridge relay 101 now pulls up and closes the circuit of 30 the slow acting relay 102. Upon energizing, relay 102 breaks the locking circuit of relay 109 and this relay falls back, restoring the circuits it controls to their original condition.

35 All three subscribers are now again connected in a three cornered talking circuit similar to the one first described. Either party in the branch exchange may now hang up and leave the other two parties to converse and if the subscriber at substation A' hangs up the subscriber at substation A² will 40 be free to release the connector D and call another number. However, it will be assumed that the subscriber at substation A², who is the party that last transferred the call, hangs up and leaves the main exchange subscriber to converse with the subscriber at substation A'. In this case the connection through the line switch C and connector H is 45 released. When the receiver is replaced at substation A² the back bridge relay 200 is deenergized, the current in the trunk is reversed, and the polar relay 106 breaks the circuit of line relay 107. The line relay and 50 slow acting relays 104, 105, and 108 now fall back. When relay 108 deenergizes, the bridge across conductors 141 and 142 is broken, for relays 109 and 103 are both at normal, and the connector H and line switch C are released and restored to normal as before explained. All the apparatus is now in the same condition as when the subscriber at substation A' was originally called by the subscriber at the main exchange. If desired, 55 the call can again be transferred, and in fact

the transferring operations can be continued as long as necessary, the incoming connector and an idle local connector being operated alternately as explained.

When the calling subscriber in the main 60 exchange hangs up, any connection which may have been established in the branch exchange is released, whether established by means of the incoming connector or by means of one of the local connectors. When the switches in the main exchange are released, which is brought about in the customary and well known manner, the bridge across the trunk conductors 12 and 13 is broken and the line relay 14 of the incoming connector D is deenergized. An instant later the release 65 relay 15 will fall back and in case the connector is in operated position the circuit of the release magnet 23 will be closed and the connector will be restored. When relay 15 deenergizes it also removes ground from conductor 51 and in case a connection is up on one of the local connectors the locking circuit of relay 109 will be broken (if this relay is energized) and also the circuit of relay 108 will be broken. This insures the opening of the bridge across the trunk conductors 141 and 142 and the local connector and line switch C are accordingly released.

Having described my invention what I 70 consider to be new and desire to have protected by Letters Patent will be pointed out in the appended claims.

What I claim is:

1. In an automatic branch exchange, incoming and local connectors, means for completing a call from the main exchange by means of one of said incoming connectors, and means for transferring the call by means of any one of said local connectors. 75

2. In an automatic branch exchange, incoming and local connectors, means for completing a call from the main exchange by means of one of said incoming connectors, and means for repeatedly transferring the 80 same call by means of a plurality of said local connectors.

3. In an automatic branch exchange, incoming and local connectors, means for completing a call from the main exchange by 85 means of one of said incoming connectors, means for operating any idle local connector to transfer the call, and means for then releasing the incoming connector without releasing the local connector.

4. In an automatic branch exchange, incoming and local connectors, means for completing a call from the main exchange by means of one of said incoming connectors, and means for operating any local connector and the incoming connector in use alternately to transfer and retransfer the call. 90

5. In an automatic branch exchange, a group of local connectors and means for operating them to complete local calls orig- 95

- inating in the branch exchange, a group of incoming connectors, means whereby a main exchange subscriber can operate one of said incoming connectors to establish connection with a desired local line in the branch exchange, and means whereby the called subscriber can operate one of said local connectors to transfer the call to another local line in the branch exchange.
10. 6. In an automatic branch exchange, a group of local connectors and means for operating them to complete local calls originating in the branch exchange, a group of incoming connectors, means whereby a main exchange subscriber can operate one of said incoming connectors to establish connection with a desired local line in the branch exchange, means whereby the called subscriber can operate one of said local connectors to transfer the call to another local line in the branch exchange, and means whereby the subscriber first called can release himself from the connection without breaking the connection to the second local line.
15. 7. In an automatic branch exchange, a group of local connectors and means for operating them to complete local calls originating in the branch exchange, a group of incoming connectors, means whereby a main exchange subscriber can operate one of said incoming connectors to establish connection with a desired local line in the branch exchange, and means for operating one of said local connectors and the said incoming connector alternately to transfer and retransfer the call.
20. 8. In an automatic telephone system, a main exchange and a branch exchange, a group of incoming connectors at the branch exchange accessible to subscribers in the main exchange for use only in completing main to branch exchange connections, a group of local connectors at the branch exchange accessible only to subscribers in the branch exchange for use in completing local connections and also for use in transferring calls initially completed by said incoming connectors, and means whereby when any connection from the main exchange is completed the incoming connector in use and one or more local connectors can be operated alternately to transfer and retransfer the call.
25. 9. In an automatic branch exchange, a local connector and means for operating it to complete local calls originating in the branch exchange, an incoming connector for completing main to branch exchange calls, means whereby a main exchange subscriber can operate said incoming connector to connect with a desired local line in the branch exchange, means whereby the called subscriber can operate one of said local connectors to transfer the call to another local line, and means whereby the subscriber first called means whereby the subscriber first called
- can disconnect himself without releasing the transferred call.
10. In an automatic branch exchange, a local connector and means for operating it to complete local calls originating in the branch exchange, an incoming connector for completing main to branch exchange calls, means whereby a main exchange subscriber can operate said incoming connector to connect with a desired local line in the branch exchange, means whereby the called subscriber can operate said local connector to transfer the call to another local line, and means for releasing the incoming connector when the subscriber first called hangs up his receiver.
11. In an automatic branch exchange, a local connector and means for operating it to complete local calls originating in the branch exchange, an incoming connector for completing main to branch exchange calls, means whereby a main exchange subscriber can operate said incoming connector to connect with a desired local line in the branch exchange, means whereby the called subscriber can operate said local connector to transfer the call to another local line, means for releasing the incoming connector when the subscriber first called hangs up his receiver, and means whereby the second called subscriber can reoperate the incoming connector to transfer the call to a third local line.
12. In an automatic branch exchange, local connectors and means for operating them to complete local calls originating in the branch exchange, an incoming connector for completing main to branch exchange calls, means whereby a main exchange subscriber can operate said incoming connector to connect with a desired local line in the branch exchange, means whereby the called subscriber can operate one of said local connectors to transfer the call to another local line, means for releasing the incoming connector when the subscriber first called hangs up his receiver, means whereby the second called subscriber can reoperate the incoming connector to transfer the call to a third local line, and means for releasing the local connector when the second called subscriber hangs up his receiver.
13. In an automatic branch exchange, local connectors and means for operating them to complete local calls originating in the branch exchange, an incoming connector for completing main to branch exchange calls, means whereby a main exchange subscriber can operate said incoming connector to connect with a desired local line in the branch exchange, means whereby the called subscriber can operate one of said local connectors to transfer the call to another local line, means for releasing the incoming connector when the subscriber first called hangs up his receiver, means whereby the second

called subscriber can reoperate the incoming connector to transfer the call to a third local line, means for releasing the local connector when the second called subscriber hangs up his receiver, and means whereby the third called subscriber can reoperate the local connector to transfer the call to a fourth local line.

14. In an automatic branch exchange, local connectors accessible only to branch exchange subscribers for completing local calls, an incoming connector initially accessible only to main exchange subscribers for completing main to branch exchange calls, means whereby a main exchange subscriber can operate said incoming connector to connect with a desired local line in the branch exchange, means whereby the called subscriber can operate one of said local connectors to transfer the call to another local line, and means whereby the called subscriber can release the local connector and call again if the line called is busy.

15. In an automatic branch exchange, a local connector accessible only to branch exchange subscribers for completing local calls, an incoming connector initially accessible only to main exchange subscribers for completing main to branch exchange calls, means whereby a main exchange subscriber can operate said incoming connector to connect with a desired local line in the branch exchange, means whereby the called subscriber can operate one of said local connectors to transfer the call to another local line, and means whereby the called subscriber can release the local connector and call another number if no answer is obtained.

16. In an automatic branch exchange, a local connector for completing local calls, an incoming connector for completing main to branch exchange calls, means whereby a main exchange subscriber can operate said incoming connector to connect with a desired local line in the branch exchange, means whereby the called subscriber can operate one of said local connectors to transfer the call to another local line, means for releasing the incoming connector, means whereby the second called subscriber can reoperate the incoming connector to transfer the call to a third local line, and means whereby the second called subscriber can release the incoming connector and call again if the line called is busy.

17. In an automatic branch exchange, a local connector for completing local calls, an incoming connector for completing main to branch exchange calls, means whereby a main exchange subscriber can operate said incoming connector to connect with a desired local line in the branch exchange, means whereby the called subscriber can operate said local connector to transfer the call to another local line, means for releasing the

incoming connector, means whereby the second called subscriber can reoperate the incoming connector to transfer the call to a third local line, and means whereby the second called subscriber can release the incoming connector and call another number if no answer is obtained. 70

18. In an automatic branch exchange, local connectors and means for operating them to complete local connections originating in the branch exchange, incoming connectors for completing connections from the main exchange, and means associated with each incoming connector whereby a local connector can be used to transfer a call. 75

19. In an automatic branch exchange, local connectors and means for operating them to complete local connections originating in the branch exchange, incoming connectors for completing connections from the main exchange, and means associated with each incoming connector whereby any branch subscriber called from the main exchange can operate one of said local connectors to transfer the call to another branch subscriber. 80

20. In a telephone system, a main exchange and a branch exchange, a trunk line extending from the main exchange and terminating in an incoming connector in the branch exchange, means whereby a calling main exchange subscriber can obtain access to said trunk line and operate said connector to extend a connection to a called line in the branch exchange, connectors in the branch exchange accessible only to branch exchange subscribers for completing local connections originating in the branch exchange, and means associated with said incoming connector whereby the subscriber on the called line can operate an idle one of said local connectors to transfer the call to another called line in the branch exchange. 95

21. In an automatic branch exchange, local connectors for completing local connections, incoming connectors for completing connections from the main exchange, and switching mechanism comprising a repeater and a line switch associated with each incoming connector whereby any branch subscriber called from the main exchange can select and operate one of said local connectors to transfer the call to another branch subscriber. 100

22. In an automatic branch exchange, local connectors for completing local connections, incoming connectors for completing connections from the main exchange, an automatic trunking switch individual to each incoming connector, means responsive to a single interruption of a called line circuit whereby any branch subscriber called from the main exchange can operate the trunking switch associated with the incoming connector in use to select an idle local connector, and means for then operating the se- 115

- lected local connector to transfer the call to another branch subscriber.
23. In an automatic branch exchange, local connectors for completing local connections, incoming connectors for completing connections from the main exchange, an automatic trunking switch individual to each incoming connector, means whereby any branch subscriber called from the main exchange can operate the trunking switch associated with the incoming connector in use to select an idle local connector, means for then operating the selected local connector to transfer the call to another branch subscriber, means for releasing the incoming connector in use, and means whereby the second branch subscriber can reoperate such incoming connector to transfer the call to a third branch subscriber.
24. In a telephone system, a trunk line extending from a main exchange to a branch exchange and terminating in an incoming connector, means for operating said connector to complete a call from the main exchange, local connectors at the branch exchange, and means for establishing a branch connection from said trunk line around the incoming connector to any idle one of said local connectors.
25. In a telephone system, a trunk line extending from a main exchange to a branch exchange and terminating in an incoming connector, means for operating said connector to complete a call from the main exchange, local connectors at the branch exchange, means for establishing a branch connection from said trunk line around the incoming connector to any idle one of said local connectors, and means for operating the local connector to which the branch has been extended to transfer the call.
26. In a telephone system, a trunk line extending from a main exchange to a branch exchange and terminating in an incoming connector, means for operating said connector to complete a call from the main exchange, local connectors at the branch exchange, means for establishing a branch connection from said trunk line around the incoming connector to any idle one of said local connectors, means for operating the local connector to which the branch has been extended to transfer the call, means for releasing the incoming connector, and means whereby the party to whom the call has been transferred can transmit directive current impulses back over said branch to reoperate said incoming connector to retransfer the call.
27. In a telephone system, a repeater and a connector permanently associated with each other, means for temporarily associating another connector with said repeater, and means in said repeater for then operating said connectors successively to connect with subscribers' lines while maintaining the said other connector in association with said repeater.
28. In a telephone system, a trunk line accessible to a calling line and having two branches terminating, respectively, in a connector and in a repeater, means for completing the connection to a called line by means of said connector, and means for extending the connection to another called line under control of said repeater while maintaining the first established connection.
29. In a telephone system, a trunk line accessible to a calling line and having two branches terminating, respectively, in a connector and a repeater, means for operating said connector to extend the first branch to a called line while maintaining the repeater in normal condition, another connector, and means for operating said last connector by means of said repeater to extend the second branch to another called line.
30. In a telephone system, a trunk line accessible to a calling line and having two branches terminating, respectively, in a connector and a repeater, means for operating said connector to extend the first branch directly to a called subscriber's line, a plurality of other connectors having access to said called line, an automatic switch for connecting said repeater with an idle one of said other connectors, and means for operating the connector so connected through the medium of said repeater to extend the second branch to another called subscriber's line while maintaining the connection through the first connector.
31. In a telephone system, a trunk line accessible to a calling line and having two branches terminating, respectively, in a connector and in a repeater, means whereby the subscriber on the calling line can control said connector to connect with a called line, another connector, and means whereby the subscriber on the called line can control the said other connector by means of said repeater to connect with another called line.
32. In a telephone system, a trunk line accessible to a calling line and having two branches terminating, respectively, in a connector and in a repeater, means whereby the subscriber on the calling line can control said connector to connect with a called line, another connector, means whereby the subscriber on the called line can control the said other connector by means of said repeater to connect with another called line, and means whereby the subscriber on the second called line can control the said first connector by means of said repeater to connect with a third called line.
33. In a telephone system, a trunk line accessible to a calling line and having two branches terminating, respectively, in a connector and in a repeater, means for completing the connection to a called line by means of said connector, and means for extending the connection to another called line under control of said repeater while maintaining the first established connection.

5 nector and in a repeater, means whereby the subscriber on the calling line can operate said connector to complete the connection to a called line, another connector accessible to said repeater, and means for operating said connectors alternately under control of said repeater to transfer and retransfer the call.

10 34. In a telephone system, a trunking connection terminating at opposite ends in automatic connector switches, a repeater and a trunk selecting switch included in the connection, means for initially operating one 15 of said connectors to connect with a called subscriber's line, and means whereby any called subscriber whose line has been connected with by either of said connectors can operate said repeater to control the other of said connectors to connect with another subscriber's line.

20 35. In a telephone system, a connector and a repeater permanently tied together, means including said connector for completing a connection from a calling to a called line, other connectors, and means for transferring the call to another called line with any idle 25 one of said other connectors and under control of said repeater.

30 36. In a telephone system, a trunk line divided at one end and terminating in a connector and a repeater, means including an automatic trunking switch and another connector for extending the repeater branch into connection with a called line, means for 35 transmitting impulses back over the extended connection to the repeater, and means in said repeater responsive to said impulses for controlling the said connector to extend the connector branch into connection with another called line.

40 37. In a telephone system, a trunk line, a repeater in said trunk line adapted to repeat impulses in either direction, an automatic switch at each end of the trunk line responsive to impulses from said repeater, a circuit for transmitting said impulses to one switch over the two sides of the trunk in series, and a circuit for transmitting said impulses to the other switch over a conductor separate from a talking circuit.

45 38. In a telephone system, a trunk line, means for establishing a flow of direct current in said trunk line, subscriber controlled means for rapidly reversing the direction of said direct current flow in said trunk line in accordance with a digit in a telephone number, and an automatic directly controlled switch operated responsive to said current reversals.

50 39. In a telephone system, a trunk line, an automatic connector switch for extending said trunk line into connection with a subscriber's telephone line, means for establishing a flow of direct current in said trunk line, and subscriber controlled means for re-

60 peatedly reversing the direction of said direct current flow in said trunk line to operate said connector to establish the connection.

40. In a telephone system, a closed line circuit including a source of direct current, an automatic switch, means for producing a series of reversals in the current flow in said circuit in accordance with a digit in a telephone number, and a polar relay in said circuit responsive to said reversals for directly controlling said switch.

45 41. In a telephone system, a trunk line, means for establishing a flow of direct current over the two sides of said trunk line in series, means for transmitting impulses over said trunk line by producing momentary reversals in the direction of current flow, and an automatic directly movable switch responsive to said impulses.

50 42. In a telephone system, a trunk line, means for establishing a flow of current over the two sides of said trunk line in series, means for transmitting impulses over said trunk line in one direction by producing momentary interruptions in the circuit, 90 means for transmitting impulses in the opposite direction by producing momentary reversals in the direction of current flow, and automatic directly movable switches responsive to the two kinds of impulses respectively.

55 43. In a telephone system, a trunk line, means for establishing a flow of current over the two sides of said trunk line in series, means for interrupting the circuit at one 100 end in accordance with the digits in a called number, means for reversing the direction of current flow at the other end in the same way, and automatic directly movable switches responsive to the interruptions and 105 reversals, respectively.

60 44. In a telephone system, a series of automatic switches including a final connector for completing a connection between a calling and called line, means in said connector for feeding battery back through one or more of said switches in the direction of the calling line, a reversing relay controlled by the called subscriber, and another automatic switch responsive to current reversals 110 produced by said relay to transfer the connection to another subscriber's line.

65 45. In a telephone system, a trunk line terminating in an automatic connector switch, a branch of said trunk line, means including a second connector switch for extending said branch into connection with a called subscriber's line, a relay in said connector controlled by the called subscriber for reversing the direction of current flow in the said branch, and a polarized relay in said branch responsive to such current reversals to operate said first connector to connect with another subscriber's line.

70 46. In a telephone system, a trunk line 130

- having an automatic connector switch at one end, means including another connector switch for extending the other end of said trunk line into connection with a subscriber's line, and means whereby the second called subscriber can reoperate the incoming connector in use to transfer the call to a third called line. 65
5. In an automatic telephone system, calling and called stations, a trunk line for extending a connection from a calling station to a called station, a repeater accessible to said trunk line, numerical switches having access to called stations, means for temporarily interposing said repeater between two of said switches, and means for alternately operating said switches into connection with called stations. 70
10. In a telephone system, an automatic switch having a line relay, a trunk line and means for extending the conductors thereof to said line relay, a bridge across said trunk line for energizing said relay, manually controlled means for producing momentary interruptions in said bridge, the said relay being responsive thereto for operating said switch to connect with a called line, and means controlled by the called subscriber for closing a second bridge across said trunk line to prevent the release of said switch in case said first bridge is permanently opened. 75
15. In an automatic branch exchange, a group of local connectors for completing calls between branch subscribers, primary line switches individual to the branch exchange lines and having access to said connectors, a group of incoming connectors, means whereby a main exchange subscriber can operate one of said incoming connectors to establish connection with a desired branch subscriber's line, a line switch individual to each incoming connector having access to said local connectors in common with said primary line switches, means responsive to a single momentary interruption of the called line circuit whereby the subscriber on the 80 called line can operate the line switch associated with the incoming connector in use to connect with an idle local connector, and means whereby the called subscriber can then operate the selected local connector to extend the connection to a second called line. 85
20. In an automatic branch exchange, a group of local connectors for completing calls between branch subscribers, primary line switches individual to the branch exchange lines and having access to said connectors, a group of incoming connectors, means whereby a main exchange subscriber can operate one of said incoming connectors to establish connection with a desired branch subscriber's line, a line switch individual to each incoming connector having access to said local connectors in common with said primary line switches, means responsive to a single momentary interruption of the called line circuit whereby the subscriber on the 90 called line can operate the line switch associated with the incoming connector in use to connect with an idle local connector, and means whereby the called subscriber can then operate the selected local connector to extend the connection to a second called line. 95
25. In an automatic telephone system, calling and called stations, a trunk line, a repeater accessible to said trunk line, switches having access to called stations, means controlled from a calling station for extending a connection to a called station via said trunk line and one of said switches, and means controlled from said called station for temporarily interposing said repeater between two of said switches to transfer said call to another called station. 100
30. In an automatic telephone system, calling and called stations, a trunk line, a repeater accessible to said trunk line, automatic switches having direct access to called stations, means controlled from a calling station for extending a connection to a called station via said trunk line, and means controlled from said called station for temporarily interposing said repeater between two of said switches to transfer said call to another station. 105
35. In an automatic telephone system, calling and called stations, a trunk line, a repeater accessible to said trunk line and associated with a non-numerical selecting switch having movement in one direction only, automatic switches having movement in two directions and having direct access to called stations, means controlled from a calling station for extending a connection to a called station via said trunk line and one of said two-directional switches, and means controlled from said called station for routing said extension to another called station via said repeater and said non-numerical selecting switch. 110
40. In an automatic telephone system, calling and called stations, a trunk line, a repeater accessible to said trunk line and associated with a non-numerical selecting switch having movement in one direction only, automatic switches having movement in two directions and having direct access to called stations, means controlled from a calling station for extending a connection to a called station via said trunk line and one of said two-directional switches, and means controlled from said called station for routing said extension to another called station via said repeater and said non-numerical selecting switch. 115
45. In an automatic telephone system, calling and called stations, a trunk line, a repeater accessible to said trunk line and associated with a non-numerical selecting switch having movement in one direction only, automatic switches having movement in two directions and having direct access to called stations, means controlled from a calling station for extending a connection to a called station via said trunk line and one of said two-directional switches, and means controlled from said called station for routing said extension to another called station via said repeater and said non-numerical selecting switch. 120
50. In an automatic telephone system, calling and called stations, a trunk line, a repeater accessible to said trunk line and associated with a non-numerical selecting switch having movement in one direction only, automatic switches having movement in two directions and having direct access to called stations, means controlled from a calling station for extending a connection to a called station via said trunk line and one of said two-directional switches, and means controlled from said called station for routing said extension to another called station via said repeater and said non-numerical selecting switch. 125

via said repeater and said non-numerical selecting switch and via another one of said two directional switches.

55. In an automatic telephone system, an established connection between a calling and a called station, said connection including a trunk line and a numerical two-dimensional switch individual to said trunk line, a repeater, a second numerical two-dimensional switch normally inaccessible to said trunk line, means in said repeater operable from said called station for interposing said repeater between said switches, and means in said repeater operable from said called station for operating said second two-dimensional switch into connection with a second called station. 70

56. In a telephone system, an established connection between a calling and a first called station, said connection including a trunk line and a first numerical switch, a repeater, a second numerical switch normally inaccessible to said trunk line, means for interposing said repeater between said switches, and means for operating said second numerical switch into engagement with a second called station. 75

57. In a telephone system, an established connection between a calling and a first called station, said connection including a trunk line and a first numerical switch, a repeater, a second numerical switch normally inaccessible to said trunk line, means for interposing said repeater between said switches, and means for operating said second numerical switch into engagement with a second called station, both said means being under control of said first called station. 80

40 58. In a telephone system, calling and called stations, a trunk line, a first automatic switch normally accessible to said trunk line, means controlled from a calling station for operating said switch into engagement with a called station, a second automatic switch normally inaccessible to said trunk line, and means controlled from said called station for connecting said second automatic switch to said trunk line for the purpose of extending the call to another called station. 85

45 59. In a telephone system, calling and called stations, a trunk line, a first automatic switch normally accessible to said trunk line, means controlled from a calling station for operating said switch into engagement with a called station, a second automatic switch normally inaccessible to said trunk line, and means controlled from said called station during a connection for making said second automatic switch accessible to said trunk line. 90

60 60. In a telephone system, calling and called stations, a trunk line, a first automatic switch normally accessible to said trunk line, means controlled from a calling

station for operating said switch into engagement with a called station, a second automatic switch normally inaccessible to said trunk line, and means controlled from said called station during a connection for making said second automatic switch accessible to said trunk line for the purpose of permitting extension of the call to another called station. 75

61. In a telephone system, a first and a second exchange, a calling station in said first exchange, called stations in said second exchange, a trunk line interconnecting said exchanges for establishing connection between said calling station and a plurality of said called stations, a repeater and a plurality of automatic switches at said second exchange, said trunk line terminating in said repeater, means for interposing said repeater between two of said automatic switches, and means in said repeater for alternately operating said switches into connection with called stations. 80

62. In an automatic telephone system, calling and called stations, a trunk line for extending a connection from a calling station to a plurality of called stations, a repeater, automatic switches, said trunk line terminating in said repeater, means for interposing said repeater between two of said switches, and means in said repeater for alternately operating said switches into engagement with called stations. 90

63. In an automatic telephone system, calling and called stations, a trunk line for extending a connection from a calling station to a plurality of called stations, a repeater, said trunk line terminating in said repeater, a first and a second automatic switch, means for interposing said repeater between said switches, and two repeating elements in said repeater for alternately operating said switches into engagement with called stations. 100

64. In an automatic telephone system, calling and called stations, a trunk line for extending a connection from a calling station to a plurality of called stations, a repeater, said trunk line terminating in said repeater, a first and a second automatic switch, means for interposing said repeater between said switches, means in said repeater responsive to rapid successive current interruptions for operating said first switch, and means in said repeater responsive to successive current reversals for operating said second switch. 110

65. In an automatic telephone system, calling and called stations, a trunk line for extending a connection from a calling station to a plurality of called stations, a repeater, said trunk line terminating in said repeater, a first and a second automatic switch, means for interposing said repeater between said switches, means in said re- 115

repeater responsive to rapid successive current interruptions for operating said first switch, means in said repeater responsive to successive current reversals for operating said second switch, and means for operating said means alternately to effect connections with called stations.

66. In an automatic telephone system, calling and called stations, a trunk line for 10 extending a connection from a calling station to a plurality of called stations, a repeater, said trunk line terminating in said repeater, a first automatic switch operable in response to successive current interruptions delivered to said repeater, a second automatic switch operable in response to successive current reversals delivered to said repeater, means for interposing said repeater between said switches, and means for 15 alternately effecting the operations of said switches to establish connections with called stations.

67. In an automatic signalling system, calling and called stations, a trunk line, a repeater, automatic switches, said trunk line terminating in said repeater, means for interposing said repeater between two of said switches, and means for alternately and successively operating said switches to establish 20 temporary connections with called stations.

68. In an automatic signalling system, calling and called stations, a trunk line, a repeater, automatic switches, said trunk line terminating in said repeater, means for interposing said repeater between two of said switches, means for alternately and successively operating said switches to establish temporary connections with called stations, and means in said switches for signalling 35 said stations.

69. In an automatic signalling system, calling and called stations, a trunk line, a repeater, automatic switches, said trunk line terminating in said repeater, means for interposing said repeater between two of said switches, and means in said repeater for alternately and successively operating said switches to establish temporary connections with called stations.

70. In an automatic signalling system, calling and called stations, a trunk line, a repeater, automatic switches, said trunk line terminating in said repeater, means for interposing said repeater between two of said switches, means in said repeater for alternately and successively operating said switches to establish temporary connections with desired called stations, and means in said switches for transmitting signals to 55 said stations.

71. In a telephone system, a trunk line associated with a repeater, an automatic switch at each end of said trunk line, telephone stations accessible to said switches, the talking conductors of said switches be-

ing conductively separated from the talking conductors of said repeater but inductively united therewith, two repeating elements in said repeater, means for operating one of said elements by rapidly interrupting the 70 circuit over the talking conductors of one of said switches, and means for operating the other of the said elements by rapidly reversing the current flow over the talking conductors leading to said other switch. 75

72. In a telephone system, a trunk line associated with a repeater, an automatic switch at each end of said trunk line, telephone stations accessible to said switches, the talking conductors of said switches being conductively separated from the talking conductors of said repeater but inductively united therewith, two repeating elements in said repeater, means for operating one of said elements by rapidly interrupting the 80 circuit over the talking conductors of one of said switches, and means for operating the other of the said elements by rapidly reversing the current flow over the talking conductors leading to said other switch, the operation of said repeating elements serving to operate said switches. 85

73. In a telephone system, a trunk line associated with a repeater, an automatic switch at each end of said trunk line, telephone stations accessible to said switches, the talking conductors of said switches being conductively separated from the talking conductors of said repeater but inductively united therewith, two repeating elements in 90 said repeater, means for operating one of said elements by rapidly interrupting the circuit over the talking conductors of one of said switches, and means for operating the other of the said elements by rapidly reversing the current flow over the talking conductors leading to said other switch, the operation of said repeating elements serving to operate said switches. 95

74. In a telephone system, a trunk line associated with a repeater, an automatic switch at each end of said trunk line, telephone stations accessible to said switches,

the talking conductors of said switches being conductively separated from the talking conductors of said repeater but inductively united therewith, two repeating elements in said repeater, one of said elements being operable by rapid current interruptions over 100 the talking conductors of said trunk line, and the other element being operable by rapid current reversals over the talking conductors of said trunk line, means for operating said elements, and means responsive to 105 the operation of said elements for operating said switches. 110

75. In a telephone system, a trunk line associated with a repeater, an automatic switch at each end of said trunk line, telephone sta- 130

- 10 tions accessible to said switches, the talking conductors of said switches being conductively separated from the talking conductors of said repeater but inductively united therewith, two repeating elements in said repeater, one of said elements being operable by rapid current interruptions over the talking conductors of said trunk line, and the other element being operable by rapid current reversals over the talking conductors of said trunk line, means for operating said elements, and means responsive to the operation of said elements for operating said switches into engagement with telephone stations.
- 15 76. In a telephone system, a trunk line associated with a repeater, automatic switches accessible to said repeater, telephone stations accessible to said switches, means for operating said repeater by rapid current interruptions over said trunk line, means for operating said repeater by rapid current reversals over said trunk line, said means being applied alternately under control of a telephone station, and means in said switches responsive to said means to operate said switches.
- 20 77. In a telephone system, a trunk line associated with a repeater, automatic switches accessible to said repeater, telephone stations accessible to said switches, means for operating said repeater by rapid current interruptions over said trunk line, means for operating said repeater by rapid current reversals over said trunk line, said means being applied alternately under control of a telephone station, and means in said switches responsive to said means to operate said switches into connection with telephone stations.
- 25 78. In a telephone system using a trunk line terminating in a repeater, the method of transferring a call from one called station to another called station, consisting in temporarily interposing said repeater between two connectors having access to called stations.
- 30 79. In a telephone system using a trunk line terminating in a repeater, the method of connecting a calling station with a plurality of called stations, consisting in temporarily associating said repeater with a plurality of connectors having access to called stations.
- 35 80. In a telephone system using a trunk line terminating in a repeater, the method of connecting a calling station with a plurality of called stations, consisting in temporarily associating said repeater with a plurality of connectors having access to called stations and of operating said connectors alternately into engagement with called stations.
- 40 81. In a telephone system using a trunk line having a repeater and associated with connector switches at each end having access to telephone stations, the method of operating said connectors into engagement with stations, consisting in alternately operating

said repeater by rapid current interruptions over said trunk line and by rapid current reversals over said trunk line, respectively.

82. In a telephone system using an inter-office trunk line associated with a two-way repeater, the method of repeating operating currents in one direction by sending rapid current interruptions to said repeater, and of repeating operating currents in the other direction by sending rapid current reversals to said repeater.

83. In a telephone system using an inter-office trunk line associated with a two-way repeater, the method of repeating operating currents in one direction by sending rapid current interruptions to said repeater, and of repeating operating currents in the other direction by sending rapid current reversals to said repeater, consisting in the provision of repeating elements in said repeater susceptible to said interruptions and to said current reversals, respectively.

84. In a telephone system using a trunk line terminating in an automatic switch having access to called stations, the method of transferring a call to another called station, consisting in temporarily associating with said trunk line a second automatic switch which is normally not accessible thereto.

85. In a telephone system using a trunk line connecting a first exchange with a second exchange and terminating in said second exchange in an automatic switch having access to called stations, the method of transferring a call to another called station, consisting in temporarily associating with said trunk line a second automatic switch which is normally not accessible thereto but provided for calls within said second exchange.

86. In a telephone system using a trunk line terminating in an automatic switch having access to called stations, the method of extending connections to a plurality of called stations consisting in temporarily associating with said trunk line a second automatic switch which is normally not accessible thereto.

87. In a telephone system using a trunk line terminating in an automatic switch having access to called stations, the method of extending connections to a plurality of called stations consisting in temporarily associating with said trunk line a second automatic switch which is normally not accessible thereto, and of alternately operating said switches into engagement with called stations.

88. In a telephone system using a trunk line connecting a first exchange with a second exchange and terminating in said second exchange in an automatic switch individual to said trunk line, the method of extending connections to a plurality of called stations, consisting in temporarily associating with said trunk line a second automatic switch which

is normally not accessible thereto but provided for calls within said second exchange.

89. In a telephone system using a trunk line connecting a first exchange with a second exchange and terminating in said second exchange in an automatic switch individual to said trunk line, the method of extending connections to a plurality of called stations, consisting in temporarily associating with said trunk line a second automatic switch which is normally not accessible thereto but provided for calls within said second exchange, and of alternately operating said switches into engagement with called stations.
- 10

90. In a signalling system wherein is provided a trunk line terminating in an automatic switching device individual thereto, the method of successively transmitting signals to a plurality of stations, consisting in temporarily associating with said trunk line a second automatic switching device which is normally not accessible to said trunk line, and of alternately operating said devices into engagement with called stations.

Signed by me at Chicago, Cook County, Illinois, this 20th day of May, 1920.

RODNEY G. RICHARDSON.
